CLAIM

The ornamental design for a display screen or portion thereof with graphical user interface, as shown and described.

DESCRIPTION

FIG. 1 is a front view of a display screen or portion thereof with graphical user interface showing a first embodiment of my new design; and,

FIG. 2 is a front view of a display screen or portion thereof with graphical user interface showing another embodiment of my new design.

The dashed broken lines illustrate text, icons, or the remainder of the graphical user interface and form no part of the claimed design. The dashed-dotted broken lines depict a boundary line of a display screen or portion thereof, and form no part of the claimed design.
